UNITED STATES PATENT OFFICE.

CHARLES S. BURTON, OF OAK PARK, ILLINOIS.

CONTAINER FOR MUSIC ROLLS AND THE LIKE.

Application filed September 7, 1922. Serial No. 586,570.

The purpose of this invention is to provide an improved construction of a tubular container for music rolls and the like having a telescoping closure. It consists in the 5 elements and features of construction shown and described, as indicated in the claims.

In the drawings:—

Figure 1 is a longitudinal vertical section of a container embodying the invention, the 10 music roll being shown therein in dotted line as closed position of the container.

Figure 2 is a similar view showing the closure, withdrawn and at position for permitting the withdrawal or insertion of the 15 roll, the roll being shown in position to which it is withdrawn by the withdrawing of the closure.

Figure 3 is a plan view of the blank from 20 which the closure member is made by folding and gluing with the flexible strip which constitutes the hinge and lug shown attached thereto preparatory to folding the blank into the form of a closure.

Figure 4 is a perspective view of the same 25 blank with the flexible strip folded back under one element of the blank to form a lug showing the element which forms the inner ply of the bottom of the closure folded up into the position which it occupies in 30 the completed closure for disclosing the lug.

Figure 5 is a perspective view showing the 35 closure in process of being folded to interlap the plies of the bottom of the fabric strip extending there-between to form by its opposite end portions respectively a hinge and a lug.

Figure 6 is a longitudinal vertical section 40 of the closure and the metal reinforce as they are connected preparatory to completing the structure by inserting the reinforce into the box, the bottom of the reinforce comprising three layers and the fabric strip extending therethrough being shown dissected,—that is, the layers being supported 45 for showing the relation of the parts more clearly.

Figure 7 is a plan view of a strip of pasteboard from which the blanks for forming 50 the closure are cut at the heavy lines indicating the outline of the blanks, and slotted at the light lines, dotted lines indicating lines of folding.

The structure shown in the drawings comprises a tubular box member, 1, having one end closed and the other end open, and 55 adapted to be closed by a telescoping closure, 2.

Said telescoping closure has one end closed, and the top and the other end open, as seen clearly in Figures 1 and 2. 60

The open end of this box is reinforced,—to compensate for lack of a head or closure at that end,—by means of a metal reinforce, 3, which is formed to telescope snugly within the open end of the box, and to admit the closure member to be telescoped through it. This reinforce is formed of a flat strip of metal folded four-square with the ends joined in any convenient way, as by lapped and soldered joint, or interlocked 70 seam, to render the reinforce as rigid as it may be in view of its thickness and breadth, the seam being preferably at the upper side of the box where any protrusion which it may cause will not encounter the closure. 75 The only securement necessary for holding this metal reinforce in place is a little glue applied to its outer surface, preferably at the corners, before it is inserted or at the moment it is inserted into the box end. 80

For hinging the closure to the tubular box and making said hinge serve as a check in the insertion of the closure in the box to closed position, as well as a check upon its withdrawal to the proper point for swinging down to open position as shown in 85 Figure 2, there is employed a fabric strip, 4, which is secured to the bottom of the closure in a particular manner, hereinafter more fully explained, and extends from the forward edge of the bottom of the closure 90 in over the lower side of the reinforce, the inner end portion being folded over the inner edge of said lower side and engaged between the same and the lower side of the 95 box member. In order to have the end engaged in the manner described between the closure and the box wall, the hinge strip is inserted through the closure and folded around its inner edge and glued down onto 100 its under side before the closure is inserted in the box.

A very important feature of a box of this type is the lug for withdrawing the closure

from the box member. The lug cannot be safely secured to the head or forward end of the closure because the constant operation of withdrawing it tends very rapidly to deteriorate the end of the closure, breaking down and causing it to be torn out. For effectiveness, the lug must be secured to the bottom of the closure so as to exert its pull in the plane of that bottom and not transverse thereto, as it would be in respect to the head end of the box if it were secured thereto. It is equally undesirable to have the lug secured by pasting or gluing upon the under side of the bottom, because in that construction it would be readily peeled off in the ordinary movement of withdrawing the closure which would be likely to occur with a downward pull. Equally it is undesirable to have the forward end of the closure perforated for extending the lug therethrough, as would be necessary if the lug were secured upon the upper surface of the bottom of the closure. All these objectionable methods of providing and securing the lug are avoided by the construction adopted, which causes the bottom of the closure to comprise three layers, one of which is continuous with the head or forward end of the closure, the other two being continuous with the sides, respectively, of the closure, the bottom being formed by folding the three parts mentioned with the first mentioned part innermost, and the other two plies successively below the first, whereby there is afforded a possibility of extending the fabric strip which forms the hinge between the said two other layers mentioned, where it may be secured by the glue which secures those two layers together, causing it to emerge as the lug, through the outer or at the forward edge of the three-ply bottom, and to emerge for the hinge at the inner edge of the same, avoiding the necessity of perforating or cutting through the head or forward end wall of the closure or the fold between the same and the inner ply of the bottom which is continuous with said head from the fold.

In detail, the method of securing the continuous fabric strip, 4, which constitutes both hinge and lug, may be understood from Figure 4 to be that said strip is glued to the under side of one of the outer or lateral plies with the proper amount extending under the middle ply to permit it to be folded back onto said outer ply and leave a double-thick lug of suitable width projecting from the inner edge of said lateral ply, and a suitable amount of its length projecting from the other edge of said ply to form the hinge and extend over the lower side of the reinforce and be folded back under the same for engagement therewith between the reinforce and the box.

From the foregoing description it will be understood that the closure is made from

a blank as seen in Figure 3 which comprises a central or main area, 10, which forms a head or forward end of the closure, a wing, 11, extending from the side of said head which will constitute the lower corner of the closure, two wings, 12, 12, extending from the two opposite sides of the central area, 10, and two wings, 13, 13, which extend from edges of said sides, 12, 12, which are in line with the fold between the parts, 10 and 11, 75 said wings, 13, 13, being in width or dimension transverse to said line or fold equal to the width in direction parallel to said line, of the head element, 10; so that when folded in the manner indicated as shown in Figure 80 5, to lap the three plies, 11, 13 and 13, as described, the said widths of the wings, 13, 13, extending from said fold line are co-terminous with said fold. The side elements, 12, 12, are extended in the line of folding mentioned, for a distance preferably somewhat greater than the vertical dimension of the box, and said wings are shaped at their upper edges in a 45°-arc about the point at which the wings, 13, 13, terminate in the blank, with a radius equal to the vertical dimension, the upper edge continuing from the arc in a direction tangent thereto at the end thereof, to the end of said side wings which are preferably cut off, as shown, so as not to terminate in a point, that is, before said tangent line intersects the line of the lower edge which is the line of fold above mentioned.

The boxes in question for music rolls are 100 customarily and desirably square in cross-section, and it is desirable for economy of material in making the closures to make the several elements, 11, 13, 13, and the portion of the element, 12, before the commencement 105 of the curve of the upper edge described, substantially square, so that the form of the blank becomes as shown in Figure 3, such that it may be cut from a parallel-sided sheet of pasteboard with minimum waste, as 110 indicated in diagram in Figure 7.

For engaging the head of the music roll to withdraw it from the box in the withdrawal of the enclosure to a sufficient distance to enable the operator to take hold of 115 it for completing its withdrawal without reaching into the box, there is provided a clip, 15, made of a straight piece of spring material, preferably spring metal, which is secured at one end near the hinged end of 120 the bottom of the closure, being bent upward from its secured portion at a slight angle, so that at its opposite end which is a distance from the head of the closure sufficient to accommodate the head of the roll, stands up 125 from the bottom of the enclosure far enough to engage the head of the roll. An up-raise of from one-eighth ($\frac{1}{8}$ ") to one-quarter ($\frac{1}{4}$ ") of an inch is sufficient for this purpose. The 130 securement of this clip to the bottom of the

closure is readily effected by forming it with two down-struck lugs, 15^a, 15^a, at the opposite sides of its inner end which will become clinched into the three-ply bottom by a blow 5 of a suitable tool.

I claim:—

1. A container for music rolls and the like, comprising a tubular box member open at one end; a telescoping closure therefor, 10 an interior metal reinforce at said open end, through which reinforce the closure telescopes into the box; a flexible fabric strip having one end engaged between one side of the reinforce, and the adjacent longitudinal 15 side of the box, and folded back over the inner edge of said side of the reinforce out through the latter and extending in the bottom of the closure secured thereto to the forward edge thereof for hinging the closure 20 to the box.
2. In the construction defined in claim 1, foregoing, the closure being integrally of flat material, cut and folded substantially as shown, in that the bottom comprises three 25 layers, of which one extends directly from the bottom edge of the outer end wall of the closure, and the other two extend from the bottom edges of the opposite side walls of the closure, said side walls extending from 30 the opposite lateral or vertical edges of the end walls, the fabric hinge being extended from the hinging portion between two of said three layers, whereby liability of strip-

ping the hinge from the bottom of the closure is avoided.

3. A container for music rolls and the like, comprising a tubular box member open at one end; a telescoping closure therefor, an interior metal reinforce at said open end, through which reinforce the closure telescopes into the box; a flexible fabric strip having one end engaged between one side of the reinforce, and the adjacent longitudinal side of the box, and folded back over the inner edge of said side of the reinforce out through the latter and extending in the bottom of the closure secured thereto to the forward edge thereof for hinging the closure to the box, the bottom of the closure comprising at least two layers, one of which is not continuous with the head of the closure from the lower edge thereof, the fabric strip being extended between the layers, whereby said strip emerges to constitute the lug without aperture through the head of the closure or the fold at its lower edge.

4. In the construction defined in claim 1, foregoing, the closure having its bottom at least two-ply and the fabric hinge being extended between said plies for emergence at the forward end of the bottom to form a lug for withdrawing the closure.

In testimony whereof, I have hereunto set my hand at Chicago, Illinois, this 5th day of September, 1922.

CHARLES S. BURTON.
